UNITED STATES PATENT OFFICE.

ANTHONY ASSALA, OF DES MOINES, IOWA.

PROPELLER.

Application filed June 23, 1922. Serial No. 570,424.

To all whom it may concern:

Be it known that I, ANTHONY ASSALA, a subject of the King of Italy, residing at Des Moines, in the county of Polk and State of Iowa, have invented a certain new and useful Propeller, of which the following is a specification.

The object of my invention is to provide a propeller with increased efficiency and durability for use in connection with aeroplanes or the like.

My invention consists in the construction of the propeller and the arrangement and combination of the propeller blades, the hub and its shaft connections, whereby the objects contemplated are attained, as herein-after more fully set forth, pointed out in my claims, and illustrated in the accompanying drawings, in which:

20 Figure 1 shows a side elevation of a propeller embodying my invention.

Figure 2 shows a rear elevation of the same.

25 Figure 3 shows a detail, sectional view on the line 3—3 of Figure 2.

Figure 4 shows a side elevation of my improved propeller, a portion of which is in section on the line 4—4 of Figure 2.

30 Figure 5 shows a detail, sectional view on the line 5—5 of Figure 2; and

Figure 6 shows a sectional view on the line 6—6 of Figure 4.

Referring to the accompanying drawings I have used the reference numeral 10 to indicate a propeller shaft of ordinary construction. This shaft is fitted into a hollow hub which comprises a substantially cylindrical body portion 11, the dimensions at the front thereof being slightly greater than 40 the dimensions at the rear. The front end is open and internally screw threaded at 12.

The cap or front end of the hub is indicated by the numeral 13 and screws into the screw threaded portion of the front of the 45 hub body. This cap is rounded and tapered from its rear to its front and along lines that will offer the least resistance to its advance through the air.

At the rear of the hub is a flange 14 keyed 50 or otherwise secured to the shaft 10 and riveted or otherwise permanently connected to the rear of the hub.

Near the front of the hub there is a flange 15 keyed or otherwise secured to the shaft, 55 and riveted or otherwise permanently connected to the hub, thus detachably fixing the

shaft within the hub and firmly bracing the hub relative to the shaft.

There are preferably two blades on my improved propeller and each is connected with and secured to the hub by means of two flanges 16 and 17 spaced apart from each other and preferably formed integral with the hub and extended laterally outwardly therefrom.

65 The blades, which are preferably made of wood, are indicated generally by the reference numeral 18, and are inserted between the flanges 16 and 17 and permanently connected therewith by rivets or the like.

70 At the outer edge of each blade I preferably provide a metal binding member 19 permanently connected with the blade by rivets or the like.

75 It is the shape of the blades and their arrangement or angularity with relation to the hub at various points which comprises an essential and important feature of my invention. As viewed from the rear, as shown in Figure 2, the forward edge of the blade 80 is indicated by the reference symbol A and the rear edge by the reference symbol B. The contour of the outer edge of the blade forms its front edge, and its rear is of gradually increasing diameter with respect 85 to the center of the hub.

In regard to the angularity of the blade relative to the hub, attention is called to Figure 5, which is taken on a section line from the center of the hub radially through the advance edge portion of the blade, and in this view it will be seen that this part of the blade inclines outwardly and forwardly relative to the line of advance of the propeller.

90 Near the central portion of the blade, as shown in Figure 4, the blade is substantially at right angles to the driving shaft and at the rear edge of the blade, as shown in Figure 3, the blade inclines outwardly and rearwardly relative to the line of advance of the propeller.

100 In addition to this, the rear outer portion of the blade is curved, as shown at C in Figure 3, in a direction rearwardly to the line of advance of the propeller.

105 By means of the features of shape and angularity of the blades just described, the following advantageous results are obtained in use:

110 Assuming that the propeller is being employed in an aeroplane and is traveling

through the air; the relative particles of air which are engaged by the blades will, before thus being engaged, be relatively stationary, or what is commonly termed still air, but as soon as any particles of air are engaged by the rapidly revolving propeller, they will commence to move in the direction in which it is being forced by the propeller blades.

10 When, for instance the advance edge of the propeller has progressed through the still air as far as, say for instance, toward the line 5—5 of Figure 2, then the previous still air that is thus engaged will be moved 15 rearwardly and by centrifugal action will have a tendency to throw it outwardly from the hub.

However, as the blade farther progresses in its revolution, it will reach farther out 20 into the still air, and before this outer circle, as it might be called, of still air has been engaged by the propeller blade and started to move rearwardly and outwardly, the outer circle of still air will oppose the travel 25 of the inner circle of still air in a direction outwardly.

In other words, the outer circumference of still air is eventually engaged and moved by the blades, and so engaged and moved 30 until after it has served the purpose of forming a cushion to prevent the inner circles of still air that were first engaged by the blades from sliding outwardly in a radial direction relative to the hub.

35 In addition to this the rear edge B of the propeller blade at its outer end is inclined rearwardly, and this, as will be seen, tends to hold the air that is being impinged by the blade against an outward or radial 40 movement, or in other words, this curvature at the rear of the blade tends to further compress the air that has been engaged by the blades and pushed rearwardly and outwardly.

45 Furthermore, by having the front edge of the propeller blade inclined outwardly and forwardly relative to a line at right angles to the shaft, and the rear end of the propeller blade inclined outwardly and rearwardly relative to a line at right angles to the shaft, the following advantage is gained:

By having the front edge of the blade inclined forwardly, a relatively larger amount 55 of still air is reached or engaged by the blade than by having the rear of the propeller blade inclined rearwardly. This air is uniformly compressed or pushed upon by

the blade and the tendency for the air to slide off of the blade outwardly by centrifugal action is minimized.

This feature may perhaps be emphasized by comparing it with blades of the class which are shaped spirally like a screw, and in blades of said class a line drawn from the axis radially at any point would show the blade to be arranged at right angles to the axis, and with such blades a considerable amount of efficiency is lost because of the still air that is impinged by the blades will at once start to move in a rearward and outward direction with relation to the blade, whereas with my improved form of the blades, this tendency is opposed in two ways:

First, by reason of the fact that the blade increases in diameter as it progresses through its effective stroke, and hence the air that is started to move outwardly and rearwardly by the advance portion of the blade is cushioned or retarded in such movement by the still air that is later engaged by the outer portions of the blade; and also the efficiency of action of my improved blade upon the air is increased by having the front edge inclined forwardly and its rear edge inclined rearwardly.

I claim as my invention:

1. An improved propeller comprising a cylindrical hub, a hub cap detachably secured to the front of the hub and shaped to offer a minimum resistance to the air, two flanges within the hub, a shaft detachably mounted in said flanges, said hub being also provided with two flanges for each blade extended outwardly therefrom and spaced apart, a propeller blade inserted between said flanges and extended outwardly from the hub and firmly secured between the flanges.

2. An improved propeller comprising a cylindrical hub, a hub cap detachably secured to the front of the hub and shaped to offer a minimum resistance to the air, two flanges within the hub, a shaft detachably mounted in said flanges, said hub being also provided with two flanges for each blade extended outwardly therefrom and spaced apart, a propeller blade inserted between said flanges and extended outwardly from the hub and firmly secured between the flanges, and a metal binder at the outer edge of the propeller blade, for the purposes stated.

Des Moines, Iowa, June 15, 1922.

ANTHONY ASSALA.
